UNITED STATES PATENT OFFICE.

THOMAS ALLATT, OF WESTFIELD, NEW JERSEY, ASSIGNOR TO INTERNATIONAL CORK COMPANY, OF BROOKLYN, NEW YORK, A CORPORATION OF NEW YORK.

CORK-FEEDING DEVICE.

1,395,248.

Specification of Letters Patent.

Patented Nov. 1, 1921.

Application filed April 27, 1920. Serial No. 377,010.

To all whom it may concern:

Be it known that I, THOMAS ALLATT, a subject of the King of Great Britain, and a resident of Westfield, in the county of Union 5 and State of New Jersey, have invented certain new and useful Improvements in Cork-Feeding Devices, of which the following is a specification.

The present invention relates to cork feeding devices, designed to feed, to cork tapering machines, flat corks, or in other words corks having each a height that is smaller than their diameter.

The main object of the present invention 15 is to provide a controlling device between a hopper and chute, which permits the corks to roll down said chute in a single row only, one on top of another, within the reach of a mechanism, presenting the same to the cutting device of the tapering machine.

Another object of the invention is to make the chute of the feeding device adjustable, according to the sizes of the corks to be fed.

25 A further object of the invention is to so mount part of the controlling mechanism on the hopper, that it can be conveniently adjusted in relation to the outlet thereof, according to the size of the corks contained 30 in the hopper.

A still further object of the invention is to construct a cork feeding device of the character described, which is simple in construction, efficient in operation and which 35 functions entirely automatically.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes 40 may be made in the size and proportion of the several parts and details of construction within the scope of the appended claims, without departing from the spirit or sacrificing any of the advantages of the invention.

50 One of the many possible embodiments of the invention is illustrated in the accompanying drawings, in which:

Figure 1 is a front elevation of a cork feeding device constructed in accordance

with the present invention, shown applied 55 to a tapering machine; Fig. 2 is a section taken on line 2—2 of Fig. 1; Fig. 3 is a section taken on line 3—3 of Fig. 2, on a larger scale; Fig. 4 is a perspective view of an agitating element employed on the 60 hopper; Fig. 5 is a side elevation of a portion of a chute constructed in accordance with the present invention; Fig. 6 is a section taken on line 6—6 of Fig. 5; Fig. 7 is a section taken on line 7—7 of Fig. 5; 65 and Fig. 8 is a section taken on line 8—8 of Fig. 5.

In the drawings, the numeral 10 indicates the frame of a cork tapering machine, on which is mounted a rotary knife 11, the flat 70 corks being held between gripping members 12 and 13, to which they are presented by an oscillating body 14. Onto this oscillating body the corks are fed from a hopper 15, into which they are placed indiscriminately, and forwarded into a chute 16. This chute terminates a substantial distance above the oscillating body 14, the latter receiving the corks from the chute and presenting the same to the grippers 12 and 13. 80 The hopper is held above the frame 10 by a bracket 17, which is mounted in any suitable manner upon the frame 10.

The slanting bottom 18 of the hopper is provided with a discharge opening 19, 85 through which the flat corks pass into a vertical extension 20 on the hopper bottom. One of the vertical sides 21 of the extension is stationary, it being fixed to the hopper bottom, while the opposite side 22, that 90 extends in parallel relation to the side 21, is movable in relation to the said stationary side, it being secured to plate members 23, which are each provided with a horizontal slot 24, through which extend clamping screws 95 25, passing into the front and rear walls 26 of the said extension. In the plates 23 are rotatably mounted the journals 27 of a horizontally extending roller 28, that projects through an opening 29 in the side wall 22 100 into the extension 20. This roller extends throughout the length of the extension, as clearly shown in Fig. 2 of the drawings, it being provided with peripheral grooves 30, in which are seated teeth 31 on the side 22 105 of the extension, the upper ends of the said teeth being disposed in a horizontal plane passing through the longitudinal axis of

the said roller. This roller rotates in the direction of the arrow shown in Figs. 1 and 3 of the drawings, it being driven from any suitable source of power, for instance, by a belt 32, passing over a pulley 32' on one of the journals thereof. Below the roller 28, the front and rear walls 26 of the extension slant toward the vertical center line of the extension, as clearly shown at 33, converging to a distance that corresponds to the diameter of the largest cork to be fed. The extension terminates in a passage 34, communicating with the chute 16. Below the roller 28, there projects into the extension a horizontally disposed roller 35, its longitudinal axis extending at right angles to the axis of the roller 28. The roller 35 is journaled in the side wall 21 of the extension and is driven from one of the journals of the roller 28, the said journal being provided for this purpose with a pulley 36, over which runs a belt 37, the latter running also over a pulley 38 on the roller 35. Guide pulleys 39 are provided, to keep the belt properly on the pulleys 36 and 38. The roller 35 rotates in the direction of the arrow shown in Fig. 2 of the drawings, it determining, with a movable section 40 on the front wall of the extension 20, the width of the passage 34. The movable portion 40 is, preferably, pivoted at 41 to the side wall 21 of the said extension, its lower end being held in fixed position by a clamping screw 42, that passes through a slot 43 in the said movable portion into the side 21 of the extension.

The passage communicates, as above stated, with the chute 16. This chute slants toward the oscillating body 14, and is made up of two spaced parallel vertical sides 44 and 45, a bottom 46 and a top 47. The side 44 and top 47 are made of one integral piece, in the form of an angle iron, that is fixed to the side wall 21 of the extension 20. The bottom 46 is adjustable in relation to the fixed top 47, it being provided with lugs 48, that abut against the side 44, said lugs being each provided with a slot 49, through which extends a clamping screw 50, the screws passing into the side 44. The side wall 45 of the chute is made up of two spaced angle irons 51, connected by links 52, which permit the distance between the said two angle irons to be varied, at will. The side 45, as a whole, is shiftable in relation to the side 44, for which purpose one of its angle irons carries clamping screws 53, that extend through slots 54 in lugs 55 on the bottom 46 of the chute. The slots 49 in the lugs 48 extend parallel to the side 44 of the chute, and the slots 54 in the lugs 55 in parallel relation to the bottom 46 of the chute, all of the said slots running at right angles to the longitudinal axis of the chute.

65 Part of the side wall 22, below the roller

28, forms a door 56, that is hinged at 57 to the said side wall. This door is shifted around its hinges when it is intended to inspect the corks, as they pass through the passage 34.

70

For agitating the mass of corks in the hopper, there extends through a slot 58' therein a curved plate member 58, having a roughened upper surface, as clearly shown at 59. This plate forms part of a cylindrical surface, adapted to rest against a curved portion 60 on the hopper bottom. The plate member 58 is fixed to an arm 61, that is pivoted at 62 to a bracket 63, the latter being attached to the side wall 21 of the extension 20. To the pivoted end of the arm 61 is fixed a bar 64, that engages with a roller 65 upon a crank arm 66. This crank arm is keyed, or otherwise fixed, to one of the journals of the roller 28. A spring 67, secured to the arm 61 and to the extension 20, serves to move the said arm toward the hopper bottom.

75

The operation of this device is as follows:—A mass of corks, to be fed to the tapering machine, is placed into the hopper 15, the size of the extension 20 and the chute 16 having been previously adjusted, so that they accommodate the corks to be fed. In making the adjustments, the set screws 25, coöperating with the plates 23, are loosened and the roller 28 and side 22 of the extension 20 shifted, so that the distance between the last-mentioned side and the stationary side 21 of the extension is slightly larger than the thickness of a flat cork. The said set screws are then screwed up to hold the movable side and roller 28 in the adjusted position. The chute 16 is adjusted so that the distance between its bottom and top is slightly larger than the diameter of an individual cork, and the distance between its sides is slightly larger than the thickness of a cork. The movable section 40 of the passage 34 is, of course, adjusted so that an individual cork can pass through the said passage.

90

95 By imparting rotation to the pulley 32', the rollers 28 and 35 are rotated and the curved plate member 58 oscillated. The oscillating plate member agitates the mass of corks in the hopper, causing them to move toward the discharge opening, through which they leave the hopper by gravity, falling onto the roller 28. This roller continuously moves and turns the individual corks over, moving them back and forth until they find their way into that part of the extension 20, which is disposed below the teeth 31 on the vertical side 22 of said extension. 105 In this part of the extension, the corks rest one on top of another with their flat ends against the sides of the extension. The roller 35 prevents a blocking of the passage 34, in that it continuously agitates the corks 110

115

120

125

130

that have been previously arranged by the roller 28, allowing them to pass singly through the said passage into the chutes 16, on which they slide down onto the oscillating body 14, the latter presenting them to the gripping members 12.

From the foregoing it appears that the corks, in passing from the hopper into the chute, are first arranged in a single plane, 10 more particularly in a vertical plane, and then agitated and controlled so that they pass in file into a passage, in registering position with the chute.

The side 45 of the chute is made of two 15 sections, that is to say angle irons 51, in order to permit the width of this side to be varied according to the requirements. At the same time, this construction of the said side permits of an inspection of the corks, 20 as they pass through the chute.

What I claim is:—

1. A feeding device for flat corks, including a hopper having a discharge opening, an extension communicating with said discharge opening having an outlet passage, a 25 roller projecting into said extension for arranging the corks therein in a single plane, and means for causing the corks to pass in file into said passage, the size of said extension and its outlet passage being adjustable and the position of said roller in re-

lation to a fixed portion of said extension being variable.

2. A feeding device for flat corks, including a hopper having a discharge opening, an 35 extension communicating with said discharge opening having an outlet passage, a roller projecting into said extension for arranging the corks therein in a single plane, and a roller also projecting into said extension for causing the corks to pass in file 40 into said passage, said rollers moving in a direction opposite to the direction of movement of the corks through said extension.

3. A feeding device for flat corks, including a hopper having a discharge opening, an extension communicating with said discharge opening having an outlet passage, a roller projecting into said extension for arranging the corks therein in a single plane, 50 and a roller also projecting into said extension for causing the corks to pass in file into said passage, said two rollers being disposed one above the other and their longitudinal axes being arranged at right angles 55 to each other, said rollers moving in a direction opposite to the direction of movement of the corks through said extension.

Signed at New York, in the county of New York and State of New York, this 29th day of December, 1919.

THOMAS ALLATT.
